(57) **CLAIM**

The ornamental design for sensor, as shown and described.

DESCRIPTION

FIG. 1 is a perspective view of a sensor, showing our new design;

FIG. 2 is a bottom plan view thereof;

FIG. 3 is a right-side elevation view thereof;

FIG. 4 is a left-side elevation view thereof;

FIG. 5 is a front elevation view thereof; and,

FIG. 6 is a rear elevation view thereof.

In the drawings, the dash-dot-dash broken lines indicate the boundaries of the claimed invention while the evenly spaced broken lines depict a number of openings or apertures through the exterior body of the sensor but that are unclaimed environment that form no part of the claimed design.
